UNITED STATES PATENT OFFICE.

HERBERT A. WRENN, OF WASHINGTON, DISTRICT OF COLUMBIA, ASSIGNOR OF ONE-HALF TO STERLING H. WATSON, OF WASHINGTON, DISTRICT OF COLUMBIA.

CALCULATOR.

1,181,819.

Specification of Letters Patent.

Patented May 2, 1916.

Application filed June 26, 1915. Serial No. 36,554.

To all whom it may concern:

Be it known that I, HERBERT A. WRENN, a citizen of the United States, residing at Washington, District of Columbia, have invented certain new and useful Improvements in Calculators, of which the following is a specification, reference being had therein to the accompanying drawing.

This invention relates to new and useful improvements in calculating apparatus, designed especially for adding, subtracting, multiplying and dividing.

The invention comprises a simple and efficient apparatus of this nature having various details of construction, combinations and arrangements of parts which will be herein-after fully described, shown in the accompanying drawings and then specifically defined in the appended claims.

20 My invention is illustrated in the accompanying drawings, in which:

Figure 1 is a front elevation of a calculating apparatus, parts being broken away to better illustrate features of the invention.

25 Fig. 2 is a central vertical sectional view through the calculator. Fig. 3 is an enlarged detail in elevation of the transferring or carrier features of the invention. Fig. 4 is an enlarged detail perspective view showing a resilient tension means. Fig. 5 is a detail perspective view of a portion of an endless chain with a modified link utilized for clearing the wheels. Fig. 6 is a detail view of a feature of the invention for imparting 30 an intermittent movement to the endless chain, and Fig. 7 is a detail view of a portion of the carrier device.

Reference now being had to the details of the drawings by numeral, 1 designates the 40 frame of the calculator which may be of any shape or size and mounted within the casing is a shaft 2 upon which a series of numeral bearing wheels 3 are journaled which carry two sets of numerals upon the projecting portion 4 thereof, one set being designated in the drawings by numeral 5 and the other set by numeral 6, the latter bearing the small numerals at the left hand corner of the face upon which the larger numerals appear.

50 Said wheels, details of which are shown in Fig. 3 of the drawings, are made preferably of a stamped up piece of metal with an integral cam 7 upon one face thereof and each wheel has a cylindrical bearing portion 7'.

55 Fastened to the upper surface of the bot-

tom of the casing is a cross-piece 8, a detail of a portion of which is shown in Fig. 4 of the drawings, and which has notches 9 upon the forward edge thereof. Resilient, bail-shaped members 10 have their opposite sides 60 passing through the notches and horizontal portions 11 pass underneath the crosspiece and the hooks 12 at the ends thereof engage over the rear edge of the cross-piece, said bail-shaped portion being disposed normally 65 at an angle, as shown in the drawings, and being resilient and serving as a tension means for the purpose presently to be described. Endless chains, made up of links 13, are connected together and every tenth link, 70 which is designated by numeral 14, a detail of which is shown in Fig. 5, differentiates from the other links in having the projecting ends 15 which are provided for the purpose of clearing the wheels. Said links engage over the projecting portions 4 which serve as the equivalents of teeth of a cog wheel and which chain also engages over a resilient, bail-shaped member 10, there being as many of said members 10 as there 75 are chains. The casing is provided with a suitable transverse slot 16 through which the numbers upon the carrier wheels may be disclosed.

80 A slide 22 is mounted at an inclination in the casing and has a lateral projection 23 projecting therefrom, movable through a slot in the end of the casing and forming a handle whereby the sheet, which contains the columns of numerals from 0 to 9, is adapted to be shifted for the purpose of adapting the apparatus for use in adding dollars and cents or for calculating numbers generally, the sheet of numerals being at its extreme 85 limit to the right when calculating dollars and cents and in which position the column of numerals at the extreme right would be obscured by the opaque portion 24 upon a transparent covering 25. When the numeral carrying sheet is shifted to the extreme left, the column of figures to the extreme left of the sheet would be covered up by the opaque strip 27 at the edge of the glass cover and the column at the extreme right would be disclosed, adapting the apparatus for use in 90 adding, subtracting, multiplying or dividing numbers. The surface upon which said columns of figures appear has preferably different colored sections, the first designated by numeral 18 being red, the shading, 100 105 110

designated by numeral 19, being green, the section 20 red and the section 21 green, forming a convenient means for indicating units, tens, hundreds, thousands, etc.

5 The means for imparting intermittent movements to the chains consists of a bar 28, a detail of one of which is shown in Fig. 6, which has an offset 29 between its ends and is apertured at 30 for the reception of one end of a spring 31, the other end of the spring being connected to an aperture 32 in the flanged bar 33, which latter also has in one edge thereof notches 34 in which the bars 28 are guided in their longitudinal movements. The lower end of each bar 28 has an angled projection 35 which projects between the links, as shown clearly in Fig. 2, and, when a downward thrust is imparted to the bar 28, said projection 10 coming against the lower end of the link will move the latter and impart a partial revolution to the carrier wheel about which the chain passes. The upper end of each bar 28 has an aperture 36 which receives 15 a pivotal pin 37, secured in an aperture 39 in the L-shaped bar 40, a detail of which is shown in Fig. 7. Said bar 40 has apertures 41 and 42 registering with each other and carries a pivotal pin 43 upon which an anti-friction roller 44 is journaled, said wheel being adapted to travel upon the surface of the cam 7.

A bail-shaped member 45 is pivotally mounted upon the pins 46 and 47, as shown 20 in solid lines in Fig. 1, and has a handle 48 projecting through a slot 49 in one wall of the casing, said bail-shaped member being positioned beyond the various series of chains and adjacent to their lower ends, 25 and a spring 50, secured to the casing, bears against the member 45 and tends to hold the same normally out of the path of the chains.

A second bail-shaped member is designated by numeral 51, the arms of which 30 near their ends are pivotally mounted upon the pins 52. A spring 53 is secured at one end to the member 51 and its other end secured to the casing at 54. A handle 55, which is secured to the member 51, is shown 35 in solid lines in Fig. 1 and in dotted lines in Fig. 5, and has a movement in a curved slot 56, the ends of the slots limiting the movement of said member in opposite directions. The transverse portion 51' of 40 the member 51 is adapted to be thrown so as to engage the several projecting portions 15 of the links 14 when it is desired to clear all of the wheels, it being understood that, before the wheels may be cleared, it will be 45 necessary to actuate the bail-shaped member 45 so that the chains will be thrown out of the paths of the projections 35 of the bars 28. In the chains illustrated, every tenth link is of the construction shown in 50 Fig. 5 and provided with the projecting

ends 15 and whatever numerals may be disclosed at the sight opening on the various carrier wheels, when the member 41 is swung down toward a horizontal position, the projecting ends 15 of the links 14 will 70 be caught thereby and the carrier wheels actuated by the various chains will be returned to 0.

In operation of the apparatus for adding, the fingers of the operator are placed 75 upon the particular numeral about which the marginal edge of the link is positioned. The chain is given a downward movement until the finger comes in contact with the edge 17. As the links of the chain turn in 80 contact with the upper transverse portion of the resilient bail-shaped member 10, the latter will spring back to its normal position, shown in Fig. 2, exerting a tension upon the chain which will tend to align the 85 numeral at the slot. When the link of a chain, representing the highest numeral in the column, is brought down to the edge 17, which designates a stop, the cam upon the face of the wheel to the right will 90 have raised the L-shaped bar 40 to its highest upper limit and, when an additional movement is imparted to the same chain to add another number, the end of the cam will pass by the antifriction roller and 95 the spring 31, which is put under tension as the bar 40 is being thrown upward, will quickly return the bar 28 to its normal position and the projection 35 coming in contact with the link upon an adjacent chain 100 will cause a partial rotary movement to be imparted to the wheel to the right, thus carrying the amount which has been added by a complete revolution of the wheel to the 105 right. This operation is repeated, the carrying being automatic from one wheel to another.

When it is desired to clear the 110 wheels or return the same to their normal positions in which 0 is disclosed on each wheel at the sight slot, the operator by pulling down upon the handle 55 may cause the bail-shaped member 51 to come in contact with the various projecting portions 15 of the links 14, causing the chains upon which they appear to be moved corresponding distances, the bail-shaped member 45 first having been tilted out of the paths of the projecting ends 35 of the bar 28. In the event of it being desired to clear any one numeral bearing wheel independent of the others, the operator may swing the bail-shaped member 45 through the medium of the handle 48, causing said member 45 to come in contact with the various chains and impart an outer movement thereto, so that they will 115 clear the projecting point 35, thus allowing the chain to be moved freely upward.

It will be noted that, when the links of the various chains pass by the resilient bail-shaped tension device 10, the latter yields 120

and quickly springs back to its normal position, causing the chain to be held taut and accurately alining the numerals upon the carrier wheels.

5 In the manipulation of the apparatus for use in subtracting, the various wheels are actuated by the chains in order to disclose the amount of the minuend by the series of numbers at the left hand corner on the projecting part of the face 4 and which are designated by numeral 6, after which the operator actuates the chains in the same manner as in addition and which will show the result by the series of numerals designated by numeral 6.

10 In the use of the calculator for multiplying, assuming for instance that it is desired to multiply 25 by 25, the finger of the operator is placed upon the numeral 2 in the tens column, in the second column to the right, and drawn down to the stop line 17 and then, by placing the finger upon the link about the numeral 5, in the units column, draws the chain down to the stop and this is repeated five times, the equivalent of adding 25 five times. Then, the finger of the operator is placed in the numeral 2 in the third column, representing hundreds, pulling down the chain to the stop line twice, 25 and thence the link, designated by numeral 5 in the tens column, twice and which is the equivalent of adding 25 twenty times. The result will appear at the sight aperture, designated through the various numerals 5.

30 In the manipulation of the calculator for division, the chains are manipulated in order to bring the various numerals 6 to designate the dividend at the sight aperture, after which the chains are manipulated as in subtraction, the dividend being treated as a minuend and the divisor as a subtrahend, that is, if in the tens column, the link designating the first numeral in the subtrahend is pulled down to the stop line 17 and then the units numeral of the subtrahend is brought down to the stop line. The quotient is indicated by pulling down the chain at the extreme left end of the series, an intermittent movement being imparted to the chain at the 40 extreme left each time a quotient numeral is to be indicated at the sight slot above. This manipulation is repeated until the number remaining in the dividend is less than the divisor, the remainder being indicated at the 45 sight aperture at the right of the sight slot.

In the manipulation of the apparatus for the various uses for which it is provided, the tension means to aline the numerals is the same, that is the yielding bail-shaped member 10 quickly applying the tension to 60 the chains to cause the numerals upon the carrier wheels to aline, and at the completion of each calculation the various wheels may be cleared, after the chains are thrown out of the paths of the projecting ends 65 35 by the tilting of the bail-shaped member 45, by simply swinging down the bail-shaped member 21 which catches the projecting ends 15 of the links, causing the various chains, wherever the projecting portions may be 70 positioned, to return the wheels to designate 0.

What I claim to be new is:—

1. In a calculating machine, a series of carrier wheels mounted therein, tension members, chains made up of links moving about said carrier wheels and said tension members, the latter adapted to aline the links of the chains.

2. In a calculating machine, a series of carrier wheels mounted therein, chains made up of links moving about said carrier wheels, stationary, bail-shaped tension members about which the links of said chains pass, the latter adapted to aline the said links.

3. In a calculating machine, a series of carrier wheels mounted therein, tension members, chains made up of links movable about the carrier wheels and said tension members, the latter adapted to aline the links of the chains, longitudinally movable, spring-pressed bars adapted to engage the links of the chains, and means for operating said bars in one direction.

4. In a calculating machine, a series of carrier wheels mounted therein, chains made up of links movable about the carrier wheels, longitudinally movable, spring-pressed bars normally in engagement with said links for causing an intermittent movement to be imparted to the chains, and means for throwing the links out of the paths of the engaging end of said bars to allow the chains to be operated in reverse direction.

In testimony whereof I hereunto affix my 105 signature in presence of two witnesses.

HERBERT A. WRENN.
